Primary Examiner — Marianne Pandozzi

CLAIM

The ornamental design for a container set, as shown and described.

DESCRIPTION

FIG. 1 is a perspective view of a container set showing my new design;

FIG. 2 is an exploded perspective view of a container set;
FIG. 3 is a right side view of the container set, the left side view (omitted) being a mirror image thereof;

FIG. 4 is a front view of the container set, the rear view (omitted) being a mirror image thereof;

FIG. 5 is a top view of the container set; and,

FIG. 6 is a bottom view of the container set.

The broken lines in the drawings are included for the purpose of illustration and form no part of the claimed design.
